Elemin J. Key of Lowell, Mass.

Assign to

The Lowell Manufacturing Company.

Letter Patent No. 7901-Dated Feb. 16, 1864.

Design for a Carpet Pattern.

III

The schedule referred to in these Letters Patent and, making part of the same.

III

To all whom it may concern:

It is known that L. Elemin J. Key, of Lowell, in the County of Middlesex and State of Massachusetts, have originated and designed a new pattern for carpets or other fabrics of which the following is a full, clear and exact description, reference being had to the accompanying drawings, making part of this specification.

This specification refers to that part of the drawings enclosed by the blue lines. A is a twelve pointed block resting on a narrow diamond frame, surrounded by a ground having an indented border.

1, 2, 3, 4, 5, 6 are halos of figures similar to A. B and C are bands running parallel with each other, having for borders lines of key work. The interiors of B and C are composed, respectively, of small regular work and small scrolls with sprigs attached.

D and E are bands, running parallel with each other and at right angles with B and C, having for borders, chains of small rings. The interiors of D and E are composed, respectively, of a diamond net work and a vine with sprigs. Bands 7 and 8, are similar to B and C. Bands 9 and 10 are similar to D and E.

The before mentioned bands intersect at various points as shown in the drawings. The remaining portions of the design are small rosettes, placed, at regular intervals upon the before mentioned bands.

The colors employed for the different portions of the design, may be varied to suit the taste and wish of the manufacturer.
